FIG. 5 INVENTOR.
OSCAR MILTON HUMPHREYS
BY Gathertonhaugh Co. ATTYS.

UNITED STATES PATENT OFFICE.

OSCAR MILTON HUMPHREYS, OF ATCHELITZ, BRITISH COLUMBIA, CANADA.

CALENDAR-CLOCK.

1,160,898.

Specification of Letters Patent.

Patented Nov. 16, 1915.

Application filed February 13, 1915. Serial No. 7,970.

To all whom it may concern:

Be it known that I, OSCAR MILTON HUMPHREYS, a subject of the King of Great Britain, and a resident of Atchelitz, in the municipality of Chilliwack, in the Province of British Columbia, Canada, have invented certain new and useful Improvements in Calendar-Clocks, of which the following is a specification.

My invention relates to improvements in calendar clocks, and the object of my invention is to devise a clock having a calendar incorporated therewith, which calendar is automatically operated by suitable mechanism actuated by the clock mechanism, thus providing a clock which not only indicates the time but also the day, date, month and year as well and which is a great convenience for either business or household purposes. I attain this object by the means illustrated in the accompanying drawings in which—

Figure 1 is a front view of the calendar as disposed within the clock case. Fig. 2 is a back view of my clock. Fig. 3 is a side view looking from the left hand in Fig. 1, the clock case being shown in section. Fig. 4 is a fragmentary side view looking from the right hand in Fig. 1, the clock case being shown in section. Fig. 5 is a fragmentary front view of the lower portion of my clock. Fig. 6 is a face view of the gears for setting the calendar mechanism by means of the hour hand. Fig. 7 is a face view of the outer half of the middle gear in Fig. 6, showing the ratchet shaped teeth. Fig. 8 is a face view of the inner half of the middle gear in Fig. 6, showing the spring dog. Fig. 9 is a plan view of the upper calendar rollers.

Similar figures of reference indicate similar parts throughout the several views.

1 indicates the case of my clock, in which is supported the usual frame 2, which in turn carries the mechanism of the clock proper and which mechanism it is not necessary to show or describe, with the exception of the usual clock spring 3, indicated dotted in Fig. 1 and full in Fig. 3, the hour hand 4, the hour hand shaft 5 and hour hand pinion 6, all as shown in Fig. 3; also the pinion 7 on the clock spring shaft 8, as shown in Figs. 1 and 3.

9 and 10 indicate vertical frames supported on the base of the clock case, being se-

cured thereto by the screws 11. Extending 55 transversely between the frames 9 and 10 and secured therein are two pairs of shafts 12—13 and 14—15, which shafts carry rotatably the calendar rollers in the following manner: Looking at the front of the clock, 60 as in Fig. 1, the day roller 16, on which are printed the days of the week, is rotatably mounted on shaft 12 at the left hand side, which roller carries, ratchet fashion, on its inner end a spring dog 17, and is provided at 65 its opposite end with a milled wheel 18 and also has formed on its periphery adjacent the milled wheel seven ratchet shaped teeth, indicated by the numeral 19, each of which teeth represents one day of the week. On 70 the remaining portion of shaft 12 is rotatably mounted the date roller 20, to which is secured one end of a ribbon, 21 in Fig. 4, on which ribbon are printed the dates, as shown in Fig. 1, the balance of the ribbon being 75 wound around a roller 22, rotatably mounted on shaft 13 so that, as the clock operates, the ribbon 21 will unwind off roller 22 on to roller 20. The inner end of roller 20 is provided with a plurality of ratchet shaped 80 teeth 23, which are engaged by the dog 17 when roller 16 is turned in the direction of the arrow, as shown in Fig. 3, and over which the dog 17 slips when the roller 16 is turned in the other direction.

85 Roller 22 is provided on its outer end with a plurality of ratchet shaped teeth 24, which are engaged by a spring dog 25 similar to the dog 17 and which dog is carried on the inner face of a milled wheel 26 rotatably 90 mounted on shaft 13, as shown in Fig. 9, so that when the milled wheel 26 is rotated in the direction of the arrow, as in Fig. 4, it will rotate the roller 22 in the corresponding direction, but when turned in the other direction its dog 25 will slip over the teeth 24 without rotating the roller 22. Rotatably mounted on the shaft 13 at the opposite end from roller 22 is a milled wheel 27, which engages the milled wheel 18 of day roller 16, so that when the milled wheel 27 is rotated in one direction it will cause the milled wheel 18 and roller 16 to rotate in the opposite direction. The peripheries of the milled wheels 26 and 27 project slightly through 100 the back of the clock case 1, as shown in Fig. 2, so that they may be actuated by hand when required.

Rotatably mounted on the lower shaft 14 at the left hand side, as in Fig. 1, is the month roller 28 provided at its outer end with a milled wheel 29, which roller 28 is in alignment with a plain roller 30 rotatably mounted on shaft 15, an endless ribbon 31 carrying the respective months being passed tightly around the rollers 28 and 30 so as to move with same as they are rotated. On the 10 remaining portion of shaft 14 is rotatably mounted the roller 32, which has the respective years printed thereon and is provided with a milled wheel 33. These rollers 28 and 32 are actuated by hand, the peripheries of 15 their respective milled wheels 29 and 33 projecting through the bottom of the case 1 for this purpose, as shown in Fig. 1.

34 indicates a shaft rotatably supported by the frame 2, as shown in Fig. 3, one end 20 of the shaft being carried through the back of the case 1 and having a pointer 35 secured thereto, which pointer is provided with a foldable finger grip member 57, shown in Figs. 2 and 3, by means of which the pointer 35 and shaft 34 may be rotated at will for a 25 purpose more fully hereinafter described. The other end of shaft 34 is extended beyond the frame 2, and has secured thereon a gear 36, shown in Fig. 3 and also in Fig. 6.

30 Rotatably mounted on shaft 34 and in gear with the pinion 7 on the clock spring shaft 8 is a gear 37, carrying on its face a spring dog 38, as shown in Fig. 1, and similar to the dogs 17 and 25. Secured to shaft 35 adjacent to gear 37 is a disk 39 carrying on its outer periphery a plurality of ratchet shaped teeth, in one of which the spring dog 38 of gear 37 is engaged so as to rotate the disk 39 when the gear 37 turns in the direction of the arrow in Fig. 1, but over which the dog slips when the gear 37 is moved in the opposite direction. Secured to the outer face of the disk 39 and near its edge are two pins 40 and 41, spaced a suitable distance 40 apart, and which pins are provided for the purpose of raising the bar 42, as more fully described hereinafter.

50 The bar 42 is slidably mounted in a vertical position on the frame 9, which frame is bent over at its upper end, as shown in Fig. 1, a slot being provided in this bent over portion and in which slot the bar 42 operates. This slot is made larger than the body of the bar to permit of the bar being moved 55 outwardly, as hereinafter described. The upper end of the bar 42 is turned over at a right angle, as at 43, so that it may be engaged at the proper time by the pin 40 to raise the bar the required height, while at a 60 suitable point below its upper end it has formed integrally with the body and offset inwardly therefrom an outstanding wedge shaped portion 44, adapted to be engaged by the pin 41 when the bar has been raised sufficiently so as to press the bar outwardly un-

til the end 43 clears the pin 40 and thus allow the bar to drop to its lowest position. As stated, the wedge shaped portion 44 is offset inwardly from the bar 42, the amount of offset being such that the pin 41 will engage the wedge shaped portion 44, as described, without extending into the path of the end 43 as it drops.

45 indicates a spring secured to frame 9 and bearing against the back of the bar 42, the purpose of which is to return the bar to its normal position after it has been operated by the pins 40 and 41.

46 indicates a pawl swingably connected to the bar 42 at a suitable point thereon, 80 which pawl engages successively each of the seven teeth 19 of the day roller 16, as shown in Fig. 3, a spring 47 being provided for the purpose of keeping the pawl in engagement with the tooth when in its effective position. 85 Extending between a lug 48 on the bar 42 and a suitable part of the frame 9 is a spring 49, which spring is in tension when the bar is raised and operates to draw the bar downward when same is released from pin 40. 90 A spring 60 is provided on bar 42, as shown in Fig. 3, which spring engages a projection 61 on the pawl 46 when it has moved the roller 16 the required amount so that it, the spring 61, will then bear on the pawl to disengage it from the tooth 19 of the roller when the bar is in its lowest position, thus permitting the turning of the roller 16 by hand to change the days up till the time the pawl is again engaged in the succeeding tooth of the roller. With reference to the action just described, it may be further explained that, unless provision was made otherwise, the pawl 46 would remain in engagement with the tooth 19 after it had moved 100 the roller 16 the desired amount, and thus the roller could not be turned backward by hand to change the days when required. To overcome this, therefore, the bar 42 is designed to drop farther than is necessary to 105 accomplish the actual turning of the roller, and, as it continues dropping, the inclination of the pawl changes until the projection 61 comes against the spring 60, whereupon the pawl is then carried downwardly by the 110 dropping bar 42 and out of the tooth 19.

115 The gear 36, hereinbefore mentioned, on shaft 34, is actuated by means of a double gear, so to speak, represented by the middle gear of Fig. 6. This gear consists of two 120 gears 50 and 51 respectively, rotatably mounted close together on shaft 52, which shaft is secured to the frame 2. Gear 50 is provided on its inner face with a plurality of ratchet shaped teeth 54, as shown in Fig. 125 7, and gear 51 is provided on its inner face with a spring dog 53, as shown in Fig. 8, which is normally engaged by the teeth 54 so that when the gear 50 rotates in the direction of the arrow in Fig. 6 gear 51 will also 130

rotate, but when gear 50 is rotated in the opposite direction gear 51 will remain stationary. Gear 50 is normally engaged by the hour hand pinion 6, while gear 51 normally engages the gear 36 on shaft 34.

Openings 55 are provided in the front of the clock case 1 and are covered with glass or other suitable material, through which openings the day, date, month, and year are at all times visible, as shown more particularly in Fig. 5. A graduated index 56 is arranged on the back of the case 1 with which the pointer 35 co-acts, the index being marked with the words "Forenoon" and "Afternoon" and with the hours, as shown in Fig. 2, so that the pointer may be set to any specified time, the purpose of which will become apparent from the following description of the operation of the device.

When the clock has been wound up and started in the usual manner the pinion 7 turns once in 6 hours. As it has eight teeth and gears with the gear 37 which has thirty-two teeth, it will be seen that the gear 37, and also the disk 39 with its pins 40 and 41 will turn once in 24 hours. Now, assuming that the rollers are set correctly and that the clock is wound up and started at 12 o'clock midnight with the pins 40 and 41 at the commencement of their 24 hour travel. The disk 39 will then move during the day bringing the pin 40 nearer to the end 43 of the bar 42 until at a certain time before the expiry of the 24 hours the pin 40 will engage the end 43 and raise the bar upwardly as the disk 39 continues moving. The distance between the pins 40 and 41 is such that when pin 40 has lifted the bar 42 to the highest point the pin 41 will have forced the bar outwardly by pressing on the wedge shaped portion 44 until, co-incident with the completion of the 24 hours, the bar 42 will be forced clear of pin 40 and pulled sharply downward by the spring 49 so that the pawl 46 will force the day roller 16 around to bring another day into view behind its opening 55.

Simultaneously with the movement of the day roller the date roller 20 will be moved to advance the date by the spring dog 17 which engages the teeth 23 of the roller 20. This operation is repeated at the completion of each 24 hours, that is at 12 o'clock midnight, until the date ribbon 21 has been wound on to the front roller 20, when it may be rewound on to roller 22 again by turning the milled wheel 26 in the direction of the arrow in Fig. 2, the pawl 46 being first disengaged from the tooth 19 to permit of the free, simultaneous rotation of the day roller as the date roller 22 is rewound. The day roller 16 may be set backward at any time during the disengagement of the pawl 46 from the tooth of the roller, as hereinbe-

fore described, by turning the milled wheel 27 by hand in the direction of the arrow in Fig. 2.

Should the clock stop and then be set on again, it will be apparent that the pins 40 and 41 will be out of their true relation to the time of their proper engagement with the bar 42, and re-adjustment is provided for by means of the index 56 and the pointer 35 secured to shaft 34. For instance, suppose the clock stopped at 3 o'clock in the afternoon, the pins 40 and 41 would be in the position corresponding to that time and the pointer 35 would indicate 3 o'clock on the index. Now suppose the clock to be set on again at 9 o'clock in the evening. At 12 o'clock midnight the pins 40 and 41 would be 6 hours behind. However, when starting the clock again the pointer 35 would be set at 9 on the index, which action would rotate shaft 34 and disk 39 and thus advance the pins 40 and 41 to their true position with reference to the proper time for operating bar 42, at the same time setting the hour hand correctly by means of the gears shown in Fig. 6.

The provision of the gear 36 and the gears 50 and 51, in engagement with the hour hand pinion 6 thus allows for the setting of the pins 40 and 41 by means of the hour hand, as it will be seen that by turning the hour hand 4 and pinion 6 forward the gears 50 and 51 will be rotated to rotate the gear 36 and thus the shaft 34, the disk 39 and the pins 40 and 41 thereon. The hour hand may be turned backward, if desired, to set the time irrespective of the calendar, as it will be seen, in that case, that the shaft 34 will not then be rotated, since the pinion 6 will only rotate the gear 50, the teeth 54 of which will slip over the dog 53 of gear 51. In this manner provision is made for moving the hour hand independently of the calendar operating mechanism. Should, however, the time be set by moving the hour hand backward, it is then necessary to move the disk 39 so that the pins 40 and 41 correspond as to their position with the corrected time, and this is done by moving the shaft 34 by means of the finger grip 57 of the pointer 35, the pointer being then set at the time on the index corresponding to the position of the hour hand of the clock.

What I claim as my invention is:—

1. In a calendar clock, the combination with a time clock having the usual clock-work mechanism, of a suitably mounted day roller provided at its outer end with seven ratchet shaped teeth arranged circularly equi-distant from each other, said roller carrying a spring dog on its inner end, a pair of suitably mounted date rollers one of which is provided with ratchet teeth adapted to be engaged by the spring dog of the day roller, a date carrying ribbon wound on

said rollers, and means co-acting with the teeth of the day roller operated by the said clockwork mechanism for imparting partial rotary movement to said roller at predetermined intervals.

2. In a calendar clock, the combination with a time clock having the usual clockwork mechanism, of a suitably mounted day roller provided at one end with seven ratchet teeth arranged circularly equi-distant from each other, said roller carrying a spring dog on its other end, a pair of suitably mounted date rollers one of which is adapted to be engaged by the said spring dog when the 10 day roller is moved in one direction to rotate therewith, a date carrying ribbon wound on said date rollers, a slidably mounted bar arranged for upward and downward movement adjacent the teeth of 15 the day roller, said bar being adapted to engage a tooth of the day roller when at its highest point, means actuated by the clockwork mechanism for raising the bar to its highest point, said means being adapted to 20 free the bar at a predetermined time, and means for then drawing the bar downwardly to impart partial rotary movement to the said day roller.

3. In a calendar clock, the combination with a time clock, of a suitably mounted day roller provided at one end with seven ratchet teeth arranged circularly equi-distant from each other and carrying on its other end a spring dog, a pair of suitably 30 mounted date rollers one of which is adapted to be engaged by the spring dog of the day roller to be moved simultaneously therewith, a date carrying ribbon wound on said rollers, a slidably mounted bar arranged for 35 upward and downward movement adjacent the teeth of the day roller, said bar being provided at its upper extremity with a projecting portion and with a wedge shaped portion below said projecting portion, a 40 pawl swingably connected to said bar and adapted to engage a tooth of the day roller when the bar is at its highest point, a rotatably mounted shaft, a disk secured to 45 said shaft, a pair of outstanding pin members 50 secured to said disk and arranged circularly thereon at a suitable distance apart, and a gear rotatably mounted on said shaft and engaging said disk, said gear being adapted to be actuated by the clockwork 55 mechanism to rotate said disk so that one of said pin members will engage the pro-

jecting portion of the bar to raise it to its highest point and the other pin member will then free the bar from the first pin member coincident with the arrival of the clock hands 60 at a specified time, and spring means for then drawing the bar down to its lowest position.

4. In a calendar clock, the combination with a time clock having the usual clockwork mechanism, of a suitably mounted day roller provided with seven ratchet teeth arranged circularly at one end and equi-distant from each other, a pair of suitably mounted date rollers one of which is adapted to be engaged by the said day roller to be rotated thereby in one direction, a date carrying ribbon wound on said rollers, a 70 slidably mounted bar arranged for upward and downward movement adjacent the teeth 75 of the day roller, a pawl swingably mounted on said bar adapted to engage a tooth of the day roller when the bar is at its highest point, means actuated by the said clockwork mechanism for raising the bar, said 80 means being adapted to free the bar at a predetermined time, means for then drawing the bar down to its lowest position, and means for then disengaging the pawl from the tooth of the day roller.

5. In a calendar clock, the combination with a time clock having the usual clockwork mechanism, suitably mounted day and date rollers, and mechanism for imparting partial rotary movement to said rollers at 90 predetermined intervals, of means operated by the forward manual operation of the clock hands for timing the operation of said rollers, comprising a gear co-operating with the said mechanism, a pinion on the 95 hour hand shaft, an idler shaft, a gear provided with ratchet teeth on its face rotatably mounted on said idler shaft and engaging said pinion, and a gear provided with a spring dog also rotatably mounted 100 on said idler shaft and engaging the first-mentioned gear, said spring dog being adapted to engage the said ratchet teeth only when the clock hands are moved forward so as to rotate the last mentioned gear.

Dated at Vancouver, B. C., this 20th day of January, 1915.
